PRINTING AND INDEX DEVICE

Filed Oct. 1, 1925

UNITED STATES PATENT OFFICE.

GEORGE W. SCHAEFER, OF QUINCY, MASSACHUSETTS, ASSIGNOR TO ADDRESSOGRAPH COMPANY, OF WILMINGTON, DELAWARE, A CORPORATION OF DELAWARE.

PRINTING AND INDEX DEVICE.

Application filed October 1, 1925. Serial No. 59,825.

This invention has relation to a frame adapted for use in a card index system, as well as to hold printing plates employed in connection with the system.

Such frames and plates are commonly used by business houses such as gas, electric light, telephone, and insurance companies, which send bills or other communications to regular customers, in conjunction with an addressing machine known as an "Addressograph," through which they are fed to produce impressions on bills or envelopes.

With the usual types of frames now extensively being employed, a printing plate of only standard width may be used with each type of frame. In other words, there are different standard frames for printing plates of different standard widths.

A salient object of the present invention is to provide an improved frame, suitable for firmly holding individual or sectional printing plates of any desired width. Another object is to provide the frame with edge flanges which may be corrected in the event that they become malformed in use.

With these and other objects and advantageous features in view, the invention consists in the novel features of construction, combination and arrangement of parts as will be more fully hereinafter described in conjunction with the accompanying drawings, wherein

Figure 1 shows in perspective view a frame embodying the present invention.

Figures 2 and 3 are perspectives of printing plates of different widths, which may be employed in connection with the frame.

Figure 4 illustrates in plan view a portion of the frame with a tab locked in position thereto.

Figure 5 is a fragmentary longitudinal section through the frame, and shows the flange or rib construction at a side edge.

Figure 6 represents in plan view a portion of a frame provided with a sectional printing plate.

Figure 7 is a section through the frame on the line 7—7 of Figure 6.

Referring to the drawings, A as a whole represents a frame embodying the present invention. The frame may be made from a single blank of suitable sheet metal, cut and constructed to a form presently to be described.

As previously indicated, provision is made to mount a printing plate on the frame so that it will be firmly held in place against any substantial movement during the printing operation, since otherwise a blurred impression will result. To this end, the lower edge of the frame is rolled in the form of a ledge or sill or bed 1, designed to support a printing plate (the plate P, for example, shown in Figure 2) against a downward motion. To prevent a forward or lateral motion of the plate, the frame is provided at either side with a lip 2 struck out therefrom and designed to engage the front face of the plate. The construction thus far described ensures against a downward, forward, backward, or lateral motion of the plate.

In accordance with the present invention, provision is made to lock a plate of any usual width onto the frame and against substantial upward movement. For this purpose, I have provided yielding latches generally indicated at 3 and located at either side of the frame above the lip 2. Each latch consists of a body portion 3^a cut substantially in the form of a triangle and integral with the frame at one end, and a stop element 4 at its other end separated at its lower portion from the main body portion 3^a by a small notch 5 and pushed forwardly sufficiently to protrude from the front face of the frame. By providing a printing plate of any width at the proper place with a suitable opening, as, for example, a slot or cutout or notch 7 at both ends of the printing plate C shown in Figure 2, to mate with the stop elements 4, it is evident that when the plate is pushed downwardly onto the frame so as to be engaged by the lips 2, and the ledge 1, the stop elements are first pushed rearwardly and then snap forward through the mating cutouts 7 to lock the plate and the frame, to prevent motion of the plate in an upward direction.

A printing plate of any other desired width (as, for example, the plate D represented in dotted outline in Figure 3), if provided with cutouts mating with the stopping elements, may be employed with the frame. In practice, the width of the printing plate is determined by the number of lines of printing thereon, and so is subject to variations. No cutouts will be necessary in the plate of minimum width P (shown in Figure

2) used in connection with the frame, since the upper edge of this plate constitutes an abutment for the stop elements 4, and precludes substantial motion of the plate. A printing plate may be removed from the frame by pushing the stop elements 4 rearwardly with the finger or any suitable instrument and then raising the plate from engagement with the lips 2, 2. The inherent springiness or resiliency of the sheet material provides the snapping action exercised by the yielding latches when a plate is mounted on the frame.

My invention may be embodied with frames having suitable keeper devices designed generally K for receiving an index tab T as more fully claimed in my divisional application Serial No. 276,054, filed May, 8, 1928.

In accordance with the present invention, the side edges of the frame are folded to and fro in successive overlying courses of progressively diminishing widths to form flanges 30 of substantially trapezoidal section. If during the use of the frame, the flanges become thickened at any portion, the successive folds may be compressed, or if they become thinned, they may be opened up with a suitable prying instrument, to produce a proper fit in the addressing machine.

In certain cases, the printing plate may be sectional, that is, it may consist of a section having a name and an address, and a smaller section having subject matter which is subject to variation, such as a telephone number or other number or amount. In such case, the larger section may be removably mounted on the frame as in Figure 1, and the smaller section S may also rest on the sill 1 and be engaged at its outer end by a lip 31 struck out from the frame, and at its inner end by a stud G which also engages the larger section and is more fully set forth and claimed in my divisional application Serial No. 281,302, filed May 28, 1928. Similarly, the frame may be provided with yielding latches for accommodating sections of different widths and having protruding stop elements 32 constructed to engage in mating slots 33 formed in the section S between its upper and lower edges, Fig. 6.

The frame may also, of course, be provided with the usual elements for holding a card or strip containing a name or any other constant or fixed data. These elements may be located at the upper portion of the frame and may comprise a bead 40, corner pocket 45 the bottom lips, 46, 46, and a side lip 47 struck out from the front face of the frame.

Having thus described an embodiment of this invention, it should be evident that various changes might be resorted to in form, construction, and arrangement of parts there-

in without departing from the spirit or scope of invention set forth in the appended claims.

What I claim is:

1. A frame of the class described for use in connection with printing plates of different widths, comprising lips struck out from the frame for retaining a plate against lateral or forward motion, a stop for preventing vertical motion of the plate in one direction, and yielding elements protruding from the face of the frame and adapted to be pushed rearwardly during the mounting of a plate and to snap through mating openings formed in the plate to prevent vertical motion of the plate in the other direction.

2. A frame of the class described for use in connection with printing plates of different widths, comprising lips struck out from the frame for retaining a plate against lateral or forward motion, a sill for supporting the lower edge of the plate and acting as a stop to prevent a downward motion of the plate, and yielding latches comprising stops protruding from the face of the frame and adapted to be pushed rearwardly while mounting a plate on said frame and to snap through mating slots formed in the plate to lock said plate to said frame against an upward motion.

3. A frame of the class described for use in connection with sectional printing plates of different widths, comprising lips struck out from the frame for retaining the plates against lateral or forward motion, a sill for supporting the lower edges of the plates and acting as a stop to prevent downward motion of the plates, and yielding latches comprising stops protruding from the face of the frame and adapted to be pushed rearwardly while mounting a plate on said frame and to snap through mating slots formed in the plates to lock the plates to said frame against an upward motion.

4. In a frame of the class described, stops protruding from the face thereof, and a printing plate having openings formed therein mating with the stops of said frame.

5. A frame of the class described, having flanges on its back side edges, comprising the edge portions of said frame bent to and fro to form overlying folds.

6. A frame of the class described, having flanges on its back side edges, comprising the edge portions of said frame bent to and fro to form overlying folds of diminishing width.

7. In a device of the class described, the combination of a frame, a printing plate having openings extending through its end edges, and yielding stops on the frame adapted to engage said openings.

In testimony whereof I have affixed my signature.

GEORGE W. SCHAEFER.
